UNITED STATES PATENT OFFICE.

ROBERT M. WALLACE AND EDWARD J. SCOTT, OF SANTA ANA, CALIFORNIA.

DEVICE FOR OPENING AND CLOSING DOORS FOR GARAGES, &c.

1,360,479.

Specification of Letters Patent. Patented Nov. 30, 1920.

Application filed January 2, 1920. Serial No. 348,930.

To all whom it may concern:

Be it known that we, ROBERT M. WALLACE and EDWARD J. SCOTT, citizens of the United States, residing at Santa Ana, in the county 5 of Orange and State of California, have invented certain new and useful Improvements in Devices for Opening and Closing Doors for Garages, &c.; and we do declare the following to be a full, clear, and exact 10 description of the invention, such as will enable others skilled in the art to which it appertains to make and use the same.

This invention relates to improvements in devices for opening and closing sliding 15 doors, and it has more particular reference to a device which is especially designed for opening doors of garages, stables, or other buildings in which vehicles are kept, although it is not to be restricted to such use.

20 The principal object of the invention is to provide a device which is of such construction and arrangement, that it may be readily and easily connected with sliding doors of a garage, a part of the door actuating device being permitted to project above the 25 ground at any desired place in the path of the vehicle, so that when the front wheel of the vehicle strikes this projecting part, the doors of the garage will be automatically 30 moved to open position, thus obviating the necessity of the driver leaving the car to open the doors as is customary.

Other objects and advantages of the invention will be apparent during the course 35 of the following description.

In the accompanying drawing forming a part of this specification and in which like numerals are employed to designate like parts throughout the same,

40 Figure 1 is an elevation of a pair of sliding doors equipped with our improved operating mechanism, looking from the outside of the garage.

Fig. 2 is a section on the plane of the line 45 2—2 of Fig. 1, looking in the direction of the arrows.

Fig. 3 is a vertical section on the plane of the line 3—3 of Fig. 1.

Fig. 4 is a view like Fig. 1, looking from 50 the interior of the garage, the doors being shown in open position.

Fig. 5 is a section on the plane of the line 55 5—5 of Fig. 2.

Fig. 6 is a detail perspective of one of 55 the operating levers.

In carrying out our invention we employ

a link and lever structure which is operatively connected to the sliding doors, and this link structure is operated by means of a crank shaft which is disposed at right angles to the doors and is in turn operated by a longitudinally movable member which is disposed in the path of the vehicle and is adapted to be engaged by one of the wheels of the vehicle.

Referring specifically to the drawings, 1 indicates a portion of a garage or other building which is equipped with a pair of sliding doors 2 mounted in any suitable manner upon a track 3. Our operating 70 mechanism comprises a pair of substantially T-shaped levers 4 connected together adjacent their lower ends by means of a link 5 which is of such construction and is so connected to these levers that it causes them to 75 move together, that is, when one lever is moved, the other lever will also be moved by reason of this link. Each lever includes a weighted head 6 which is adapted to be disposed between a pair of shoulders 7 carried 80 by each of the doors 2. The shoulders here shown are in the form of vertical strips of wood or battens, although they may be of any other construction. The levers, or at least the heads of the levers, are confined 85 between the battens 7 by means of a metal plate 7^a secured transversely across the battens. Heads 6 of the levers 4 normally bear 90 against one of the battens 7 on each door. For instance, as shown in Fig. 1 the heads 90 bear against the meeting battens when the doors are in closed position and they are moved to a position to engage the opposite battens when the doors are in open position 95 as shown in Fig. 4. Such action of the levers is due to the fact that the heads carried thereby are made of lead or some other heavy material, and when they pass a vertical position they drop either one way or the other by gravity against one of the battens and thus serve to move the door in a direction according to the direction which the levers fall. One of the levers is pivoted, as shown at 8, at its lower end to a suitable support, such as for instance a plurality of boards which are placed in the ground. On the other hand, the other lever is provided with a non-circular aperture 9 adjacent its lower end through which the flat-faced portion 10 of the crank shaft 11 100 extends, thus serving to swing the lever either to the left or the right when the

crank shaft is rotated. The crank shaft and other mechanism for operating the levers 4 is housed in a suitable supporting structure which we have indicated at 12, 5 said structure being composed of boards, bricks, or any other suitable means placed below the surface of the ground. Crank shaft 11 is journaled at its opposite ends in this above mentioned supporting structure 10 12. This crank shaft differs in construction from those commonly used in engines and the like, as it is preferably made from a single heavy bar and is bent laterally as shown at 13 and 14 and is connected by an 15 oblique portion 15 with which the vehicle operated actuating member 16 co-acts and causes the shaft to rotate, which in turn rocks the levers 4 which operate the doors. Member 16 may be of any suitable formation and may coat with the crank shaft in any suitable manner, but I prefer to employ a substantially U-shaped frame 17 which is pivoted upon a shaft 18 extending transverse of the crank shaft and carried by the 20 supporting structure 12. Between the free ends of this U-shaped frame 17, I attach, in any suitable manner, a roller 19 which is designed to engage the portion 15 of the crank shaft and cause it to rotate. This 25 member 16 is so designed and is so pivoted on the shaft 18 that a portion thereof extends above the surface of the ground, and this portion is adapted to be engaged by one of the front wheels of the automobile, 30 and swung on its pivot longitudinally of the crank shaft. 35

The member 16 will be positioned in the path of the automobile entering a garage. When the doors are closed, the heads of the 40 levers 4 bear against the meeting battens of the doors and the crank shaft 11 is in the position shown in full lines in Figs. 1 and 2. When in this position the roller 19 bears on the portion 15 at a point somewhat close to 45 the laterally bent portion 13. In approaching the entrance of the garage, the left front wheel of the vehicle will come into engagement with the portion of the U-shaped frame 17 which projects above the surface 50 of the ground, and when it is set into motion it will move in a direction longitudinally of the crank shaft 11 and the roller 19 will ride upwardly on the now inclined portion 15 of the shaft and cause it to rotate in a direction from right to left until it assumes 55 the position shown in dotted lines in Fig. 2. Such rotation of the crank shaft will also cause one of the levers 4 which is keyed thereto to swing away from the batten 7, 60 with which it is now engaged, toward the unengaged batten. As soon as this swinging lever 8 reaches a vertical position it will swing by gravity against the unengaged batten, striking it hard enough to force the 65 doors apart or to open position. Inasmuch

as these levers 4 are connected by the link 5 the same motion will be imparted to both levers, that is, they will move in a direction away from each other. When the owner leaves the garage, he will grasp the member 70 16 and move it in a direction opposite to that just specified, thus causing the crank shaft to revolve to its normal position, whereby the doors will be moved to closed position. In an apparatus of the kind described it will 75 not be necessary for the crank shaft to rotate very much, because as soon as the crank shaft rotates enough to bring the levers to a vertical position, it will have no further action on said levers as they, from that point 80 on, move by gravity and open the door without further help of the crank shaft.

While we have described our device as being especially adapted to be used in connection with the opening and closing of 85 garage doors, we desire it to be understood that it may also be employed in connection with any other type of sliding doors. In a device of the above mentioned construction it will be seen that it will be operated solely 90 by means of the vehicle, and with such a device it will not be necessary for the driver to leave the car to open the doors as is customary. Our device is simple in construction, highly efficient in use, and is of such 95 construction that it may be readily installed for use on sliding doors of any construction without changing the construction of the door or framework upon which it is mounted. 100

It is to be understood that the form of our invention herein shown and described is to be taken as a preferred form of the same and that various minor changes in the shape, size, and arrangement of parts may 105 be resorted to without departing from the spirit of the invention or the scope of the subjoined claims.

We claim:

1. In a door actuating device, in combination, sliding doors, a lever and a link structure operatively engageable with the doors, a support, a crank shaft journaled at its opposite ends in said support and rigidly connected to one of the levers, and means 110 movable longitudinally of the crank and engageable therewith to rotate it, said means including a portion extending above the ground to be engaged by a vehicle wheel. 115

2. In a door actuating device, in combination, sliding doors, a link and lever structure engageable with said doors, a supporting structure disposed at right angles to the doors, a crank shaft journaled in said supporting structure and rigidly connected with 120 one of said levers, a rod disposed transversely of the support, a substantially U-shaped frame pivoted on said rod, a portion 125 of the frame extending above the ground, a roller carried by the free ends of the frame 130

and engageable with the crank shaft, whereby when the frame is swung longitudinally of the crank shaft the roller will engage said shaft and rotate it.

- 5 3. A closure actuating device, in combination, a sliding door provided on one side along its vertical edges with spaced strips, a plate secured to and extending transversely across the outer faces of the strips, a base, a
10 lever pivoted at its lower end to the latter, said lever being provided at its upper end with a weighted T-head disposed between the door and plate and also between said strips, it having a limited movement between
15 the latter and normally bearing against one of them and being held in proper position by the plate, and means to actuate the lever so that when it passes a certain vertical position it will fall by gravity against the unengaged strip and automatically open the
20 door.

4. A closure operating device, in combination, a pair of sliding doors including spaced

vertical strips arranged along their vertical edges, a base disposed below the lower edges 25 of the doors, a pair of levers pivoted at their lower ends to said base and having their upper ends arranged between the strips on the door, means carried by the strips for confining the last named ends of the levers 30 between them, a rock shaft to which one of the levers is rigidly secured, a connecting link having its opposite ends curved laterally in opposite directions, the downturned end being pivoted to the lower end of one 35 of the levers between the latter's point of connection with said base, and the upturned end being pivotally connected to the other lever at a point above its pivotal connection with the base, and vehicle actuated means 40 coöperating with the shaft for actuating it.

In testimony whereof we have hereunto set our hands.

ROBERT M. WALLACE.
EDWARD J. SCOTT.
